Inventor:
George Ludwig
By: W. J. Kelly

UNITED STATES PATENT OFFICE.

GEORGE LUDWIG, OF CHICAGO, ILLINOIS, ASSIGNOR TO R. WILLIAMSON & COMPANY, OF CHICAGO, ILLINOIS, A CORPORATION OF ILLINOIS.

CHANDELIER.

Application filed August 5, 1921. Serial No. 489,992.

To all whom it may concern:

Be it known that I, GEORGE LUDWIG, a citizen of the United States, residing at Chicago, in the county of Cook and State 5 of Illinois, have invented certain new and useful Improvements in Chandeliers, of which the following is a specification.

The object of this invention is to generally improve chandeliers for electric lights, and 10 particularly to provide for the ready passage of the lighting wires through the body of the chandelier to the bulbs.

More specifically, my object is to replace the conventional loop and hickey with an 15 improved loop providing passages for the wires through which the latter may be inserted with ease and speed.

In the accompanying drawing which illustrates one embodiment of the invention

20 Fig. 1 is an elevation partly in section of a chandelier embodying my invention.

Fig. 2 is a section on the line 2—2 of Fig. 1 with the outer portion of the body broken away.

25 Referring to the drawing, 10 indicates the usual canopy and 11 the chain through the links of which the wires 12 are laced and descend from the canopy to the body 13. The body 13 is, in this case, made of an upper portion 14 and a lower portion 15; and distributed about the periphery of the body are a suitable number of arms 16 from which the pendant bulb sockets 17 project. Assembled with the lowest link of the chain 30 is a loop 18 which may have any desired form of artistic appearance. As I have shown it, the bottom is equipped with scrolled knobs 19 forming shoulders which rest against the upper side of the top section 40 of the body.

The sides 21 and 22 of the loop extend below this shoulder through the opening 27 in the top piece 14 and well within the body 13. The lower end of the sides are connected by 45 a short bar 23 having in its center a threaded opening 24 adapted to receive a threaded pipe or rod 25 extending through the bottom 15 and receiving the knob 26. With this construction the wires pass freely between 50 the lower ends of the sides 21 and 22, by the

cross bar 23 and on to the bulb sockets carried by the arms 16.

My invention simplifies the construction of chandeliers and reduces the number of parts required so that the chandelier can be 55 manufactured at lower cost than has been customary heretofore. And it enables the parts to be easily and quickly assembled and secured together to produce a strong, rigid chandelier. With this construction I am enabled to dispense with the necessity for a 60 separate hickey which is usually secured directly or indirectly to the loop to enable proper distribution of the conductor wires and I provide a single connection between 65 the one-piece loop and the knob to secure these parts rigidly together with the body held therebetween.

I am aware that various changes in the form and proportion and arrangement of 70 parts of my invention may be made without departing from the spirit and without sacrificing any of the advantages thereof and I reserve the right, therefore, to make all such changes as fairly fall within the scope of the 75 following claims:

I claim:

1. A chandelier comprising a body having an opening therein, a one-piece loop seated in said opening, shoulders on the loop engaging the top of the body to space the lower end of the loop within the body so that the lower end of the opening between the sides of the loop will be located within the body below the top thereof to permit distribution 85 of the conductor wires within the body, and means for securing the loop to the body.

2. In a chandelier, comprising a body having openings in the top and bottom thereof, a one-piece loop seated in the top opening 90 and arranged to have the lower end of the opening between the sides of the loop opening laterally within the body, a knob, and a rod connected to the lower end of the loop within the body and extending through the 95 opening in the bottom of the body and connected to the knob to rigidly secure the parts together.

3. A chandelier comprising a body having an opening in its top, a one-piece loop 100

2
seated in said opening and having a cross-piece at its bottom, shoulders on the loop engaging the top of the body so that the lower end of the opening between the sides of the loop will be located within the body below the top thereof to permit distribution of the conductor wires within the body, a

knob to engage the bottom of the body, and a one-piece connection engaging the cross-bar of the loop and extending through the bottom of the body to engage the knob for rigidly securing the parts together.

GEORGE LUDWIG.
